UNITED STATES PATENT OFFICE.

WILLIAM E. SHARP, OF CHICAGO, ILLINOIS, ASSIGNOR TO GRIP NUT COMPANY, OF CHICAGO, ILLINOIS, A CORPORATION OF ILLINOIS.

ANTICREEPING RAIL-LOCK.

1,174,295.

Specification of Letters Patent.

Patented Mar. 7, 1916.

Application filed August 5, 1915. Serial No. 43,763.

To all whom it may concern:

Be it known that I, WILLIAM E. SHARP, a citizen of the United States of America, residing at Chicago, in the county of Cook 5 and State of Illinois, have invented certain new and useful Improvements in Anticreeping Rail-Locks, of which the following is a description.

My invention belongs to that general class 10 of devices adapted to be firmly locked upon the base of the rail, and to so engage the side of the tie that the tendency of the rail to creep owing to differences in temperature may be overcome.

15 To this end my invention consists in the novel construction, arrangement and combination of parts herein shown and described, and more particularly pointed out in the claim.

20 In the drawings, wherein like reference characters indicate like or corresponding parts, Figure 1 is a side elevation of my invention, showing a rail in cross section seated therein, the position slightly exaggerated to more clearly show the construction. Fig. 2 is a plan view of the same, with rail 25 shown in dotted lines, and Fig. 3 is an end view, showing the bolt in place.

As shown in the drawings, 1 indicates a 30 suitable base or body provided at one end with an overhanging shoulder 2 constructed to engage and extend above and partially over one edge of the rail flange 3 seated on the device. The opposite end 4 of the device 35 is strongly constructed, and has formed therein a bolt hole upwardly and outwardly inclined, as shown, in which is positioned a coöperating bolt 5, with its threaded end upward provided with a suitable nut 6. The 40 inclination of the bolt is such that the lower edge of the tilted nut tends to conform to the upper face of the flange near its edge,

engaging the same, and as the nut is turned down on the bolt, forces the flange firmly against the engaging shoulder 2, and at the 45 same time firmly locks the proximate edge of the flange to the device.

The marginal edges of the device are 50 strongly reinforced as at 7, 8, 9, 10 and 11, one of said depending reinforced parts, as 11, being adapted to be positioned against the side of a tie 12, as shown in Fig. 3. It will thus appear that firmly locking the lock to the rail, and with the side of the lock firmly contacting with the bedded tie, tends 55 to prevent the rail from creeping, as stated.

Having thus described my invention, what I claim as new and desire to secure by Letters Patent is:—

An anticreeping rail lock, comprising a 60 suitable body provided with a depending part adapted to lie in contact with the side of a tie, said body having a rail seat upon its upper surface with an overhanging shoulder upon one end adapted to engage and 65 partly embrace the flanged edge of a rail seated thereon, the opposite end having formed therein an upwardly and outwardly inclined bolt hole, in combination with a coöperating bolt seated in the hole with its 70 threaded end upward, and a nut therefor, whereby upon turning down the nut on the bolt the proximate edge of the rail flange placed thereon will be engaged and the rail firmly locked in its seat and engaging the 75 side of the tie.

In testimony whereof, I have hereunto signed my name in the presence of two subscribing witnesses.

WILLIAM E. SHARP.
